UNITED STATES PATENT OFFICE

HEINRICH HENGSTLER, OF OBERWINTERTHUR, SWITZERLAND

CLIP, CLASP, AND LIKE FASTENING FOR NECKTIES

Application filed December 11, 1929, Serial No. 413,263, and in Germany April 20, 1929.

I have filed applications in Germany, on the 20th April, 1929; Switzerland, on the 7th May, 1929; and Austria, on the 16th October, 1929.

5 The present invention relates to clips, clasps and like fastenings of the kind in which a member is provided which resembles in its form and appearance a tied bow or knot of the usual kind and into which the 10 two ends of the necktie are inserted.

Longitudinally slitted clip devices or sheaths for neckties are already known wherein the parts of the tie are held firmly in position by means of clamping members 15 arranged in the interior of the clip device. This construction necessitates the employment of a complicated mechanism which renders the device expensive and inartistic. The present invention renders it possible to 20 obtain with a clip device of the simplest possible construction, a perfect imitation of a necktie which has been tied into a knot in the ordinary way.

According to the invention the clip device 25 comprises a sheath provided with a clamping member which is resilient and is curved inwardly towards the interior of the sheath in such manner that when the tie has been introduced into the sheath and the clamping 30 member brought into the closed position, the tie is firmly clamped between the inner wall of said sheath and said clamping member.

A preferred constructional form according to the invention is illustrated by way of example on the accompanying drawings, in which:

Fig. 1 is a front view of a device according to the invention,

Fig. 2 is a plan of the device,

40 Fig. 3 is a back view of the device, and

Fig. 4 shows the necktie "tied" by means of the clip according to the invention.

Referring to the drawings the reference letter *a* denotes the clip device or sheath proper, the construction and shape of which corresponds to the shape of an ordinary knot tied in a necktie, and which is slitted longitudinally. On one of the longitudinal edges of the slit a clamping member *b* is pivoted, 50 which is provided with a tongue *c* adapted

to be clasped to and unclasped from a corresponding slit on the other longitudinal edge of the slit for the purpose of holding the tie in position or releasing it. In order that the sheath should not be noticed when the 55 tie is worn it is preferably covered with similar material to that of the tie itself; but it may also be provided with painted or impressed designs.

The "tying" of a necktie by means of the 60 device is effected by passing the two end lengths of the tie through the slit into the interior of the sheath and then clamping them in place by means of the clamping member. By pulling the ends of the tie or sliding 65 the sheath upwards the device can be brought into the position which would otherwise be occupied by the ordinary knotted tie so that it resembles and replaces the latter.

I claim:

In a clip device for a necktie, of the kind set forth, the combination of: a longitudinally slitted sheath, and a resilient clamping member hinged to said sheath and curved inwardly towards the interior of the latter in such manner that when it is in the closed position the tie is clamped between the inner wall of said sheath and said clamping member, substantially as and for the purpose specified.

Signed at U. S. Consulate General, city of Zurich, Confederation of Switzerland, this 11th day of November, 1929.

HEINRICH HENGSTLER.
